UNITED STATES PATENT OFFICE

GEORGE REA, OF BROOKLYN, NEW YORK

DESIGN FOR A WATCHCASE

Application filed October 4, 1929. Serial No. 32,940. Term of patent 7 years.

To all whom it may concern:

Be it known that I, GEORGE REA, a citizen of the United States, and a resident of Brooklyn, in the county of Kings, State of New York, have invented a new, original, and ornamental Design for Watchcases, of which the following is a specification, reference being had to the accompanying drawing, forming a part thereof.

I claim:

The ornamental design for a watchcase as shown.

GEORGE REA.
